UNITED STATES PATENT OFFICE.

WALDEMAR KOPS, OF NEW YORK, N. Y., ASSIGNOR, BY MESNE ASSIGNMENTS, TO
KOPS BROTHERS, OF NEW YORK, N. Y., A COPARTNERSHIP.

APPAREL GARMENT.

Application filed October 5, 1922. Serial No. 592,473.

To all whom it may concern:

Be it known that I, WALDEMAR Kops, a citizen of the United States, residing in the borough of Manhattan, city, county, and 5 State of New York, have invented an Improvement in Apparel Garments, of which the following is a specification.

This invention relates to an apparel garment and more particularly to that type of 10 garment shown and described in my applications, Serial Nos. 491,103, filed August 10, 1921, and 554,521, filed April 18, 1922. This type of garment is one that is made to wear next to the body as a combined 15 under vest, corset and brassière, the garment performing the functions of all three of the garments named so that instead of wearing three garments in the use of my improved garment but one may be worn. 20 This garment is preferably made of relatively light weight material which is sufficiently yielding to permit the garment to perform its intended functions and sufficiently soft to prevent the garment from injuring the skin. The material of which the 25 garment is constructed is also preferably a washable material so that the garment may be laundered in the usual manner of laundering under garments. While this garment is adapted for general use it is particularly serviceable as an under garment 30 to be worn in athletic sports, dancing and other similar exercises where entire freedom of movement of all parts of the body is necessary or desirable and which cannot be obtained in the use of stayed corset garments 35 as commonly constructed. Furthermore, and to this end, the garment is so constructed as to completely cover the body 40 from substantially the bust to the thighs and to support and confine the busts as well as to confine the hips, thighs and abdominal portions of the body of the wearer.

The garment made in accordance with 45 the present invention preferably comprises a bust member which is adapted to extend around the body from the front to the back and to be adjustably connected at the back of the wearer, together with a hip, thigh 50 and abdominal member adapted to extend around the body preferably from the back to the front and to be adjustably connected at the front of the body. The bust member is adapted to support and confine the busts, 55 and the hip, thigh and abdominal member is

adapted to confine and lend support to the underlying portions of the body of the wearer. The garment is so constructed that the upper front portion of the hip, thigh and abdominal member is adapted to overlie the front central portion of the bust member and the overlapping portions of these members at the front thereof are provided with means for maintaining the same in their relative positions. Furthermore, 60 the members of the garment may be connected by suitable shoulder straps.

The garment made in accordance with my present invention will be hereinafter more particularly described in conjunction 70 with the accompanying drawings, in which,—

Fig. 1 is a perspective view illustrating the use of the garment.

Fig. 2 is a plan view showing the members of the garment in a substantially flat or spread out position, and

Fig. 3 is an enlarged front elevation of the garment.

Referring to the drawing, it will be seen 80 that the bust member may be made of similarly formed sections 10 and 11 depending from which are the lower front sections 12 and 13. These sections of the bust member are connected along a central line of stitching indicated at 14. The end of the section 10 is fitted with a reinforcing strip 15 extending from which are straps 16 and 17 each provided with a series of eyelets as indicated at 18 and 19. The corresponding 90 end of the section 11 is also provided with a reinforcing strip 20 to which there are connected straps or tapes 21 and 22 having connected thereto hooks 23 and 24 adapted, respectively, to engage any pair of eyelets 95 18 and 19 whereby the bust member after being passed around the body may be adjustably connected to position thereon. The lower edges of the bust member are preferably tapered and curved as indicated at 100 25 and 26, while the upper edges are preferably inclined as indicated at 27 and 28 at the sides, and the central upper edge 29 is preferably straight and adapted to extend directly across the body in a substantially 105 horizontal position. The lower edge, preferably at the center thereof, is provided with a strap 30 attached to which there is a hook 31 for a purpose hereinafter described, and the lower front sections 12 and 110

18 are provided with buttons 32 and 32' also for a purpose to be hereinafter described.

The hip, thigh and abdominal member 5 may also be constructed in sections, and as illustrated the same consists of back sections 33 and 34 connected along a line of stitching 35 and side sections 36 and 37, the former of which is connected to the back 10 section 33 along a line of stitching 38, while the latter is connected to the back section 34 along a line of stitching 39. In the lower edge of this member I also prefer to employ gore sections 40 and 41. The gore section 15 40 is placed between the sections 33 and 36, while the gore section 41 is placed between the sections 34 and 37. This member also includes front sections 42 and 43. The front section 42 is connected to the side 20 section 36 along a line of stitching 44, and the front section 43 is connected to the side section 37 along a line of stitching indicated at 45. At the edge of the front section 42 there is a reinforcing strip 46 in 25 which there is a series of eyelets 47. Similarly at the edge of the front section 43 there is a reinforcing strip 48 in which there is a corresponding series of eyelets 49. This member of the garment may also include 30 top sections indicated at 50 and 51 connected along its lower edge to the upper edges of the sections forming the lower part of the garment. The upper sections 50 and 51 may be made of the same material as the 35 other sections of this member of the garment, or of any other material, and the section 50 may be connected to the section 10 of the bust member by means of a shoulder strap 52, while similarly the section 51 may 40 be connected to the section 11 of the bust member by a shoulder strap 53. At the lower edge of the hip, thigh and abdominal member and preferably depending from the gore sections 40 and 41, I may employ suitable 45 hose supporters 54 and 55. The lower edges of the side and front sections of this member of the garment may be tapered or cut away as indicated, respectively, at 56 and 57.

50 In the use of the garment, the bust member is passed around the body from the front to the rear and the hook members 23 and 24 caused to engage the eyelets 18 and 19 to adjustably secure this member of the garment 55 in position on the body, and then the hip, thigh and abdominal member is passed in the opposite direction around the body and a lace 58 threaded through the eyelets 47 and 49 in order to adjustably connect the 60 ends of this member and secure the same in position on the body. As hereinbefore stated, the upper front portion of the hip, thigh and abdominal member is adapted to overlie the lower front central portion of the bust member in order to cause the gar-

ment to completely cover the body from the bust to the thighs, and to maintain these overlapping portions of the garment in position the hip, thigh and abdominal member is preferably provided with button holes 59 and 59' adapted to receive the buttons 32 and 32' respectively, it being understood that the button holes in which the buttons are engaged are dependent upon the adjustment to position of the lower member of the garment. To the same end, as will now be understood, the hook 31 on the tape 30 may be caused to engage a portion of the lace 58 to assist in maintaining these overlapping portions of the garment in position.

I claim as my invention:

1. An apparel garment adapted for use as a combined undervest, corset and brassière and to completely cover the body from the busts to the thighs, comprising a bust member adapted to pass around the body and to be secured in position thereon, a hip, thigh and abdominal member also adapted to extend around the body, means for securing the hip, thigh and abdominal member in position at the front of the body, the upper front portions of the hip, thigh and abdominal member being adapted to overlie the lower front portions of the bust member, means attached to the lower front portions of the bust member on both sides of the front central line thereof for engaging the overlying front portions of the hip, thigh and abdominal member for maintaining these parts in position on the body, and a device connected to the lower edge of the bust member in a centrally disposed position for engaging the means for securing the hip, thigh and abdominal member on the body to also maintain the relative positions of the upper front portions of the hip, thigh and abdominal member and the underlying front portions of the bust member.

2. An apparel garment adapted for use as a combined undervest, corset and brassière and to completely cover the body from substantially the busts to the thighs, comprising a bust member adapted to pass around the body from the front to the back to confine and support the busts, means for adjustably connecting the ends of the bust member to one another, a hip, thigh and abdominal member adapted to extend around the body from the back to the front to confine and assist in supporting the underlying portions of the body, means for adjustably connecting the edges of the hip, thigh and abdominal member at the front thereof, the upper front portions of the hip, thigh and abdominal member overlying the lower front portions of the bust member, attaching devices secured to the lower front portion of the bust member on either side

of the front central line for engaging the overlying portions of the hip, thigh and abdominal member to maintain the relative positions of these parts on the body, and a device secured to the lower front edge of the bust member in a centrally disposed position for engaging the means for adjustably connecting the edges of the hip, thigh and abdominal member for also maintaining the relative positions of the overlapping front portions of the garment.

3. An apparel garment adapted for use as a combined underwest, corset and brassière and to completely cover the body from substantially the busts to the thighs, comprising a bust member adapted to pass around the body from the front to the back to confine and support the busts, means for adjustably connecting the ends of the bust member to one another, a hip, thigh and abdominal member adapted to extend around the body from the back to the front to confine and assist in supporting the underlying portions of the body, means for

adjustably connecting the edges of the hip, thigh and abdominal member at the front thereof, the upper front portions of the hip, thigh and abdominal member overlying the lower front portions of the bust member, buttons attached to the lower front portions of the bust member on either side of the front central line thereof and adapted to engage in button holes similarly placed in the overlying portions of the hip, thigh and abdominal member for maintaining the relative positions of these parts of the garment on the body, a tape connected to the lower front central portion of the bust member, and an attaching device secured to the said tape and adapted to engage the means for adjustably connecting the edges of the hip, thigh and abdominal member to also maintain the relative positions of the overlapping portions of the garment when in use.

Signed by me this 19th day of Sept., 1922.

WALDEMAR KOPS.
